P. H. UNSINGER.

SAFETY RAZOR.

APPLICATION FILED MAY 17, 1919.

1,323,731.

Patented Dec. 2, 1919.

FIG. 1.

FIG. 2.

FIG. 3.

Philip H. Unsinger ^{INVENTOR}
BY *Frederick Thompson*
ATTORNEYS.

UNITED STATES PATENT OFFICE.

PHILIP H. UNSINGER, OF GENEVA, NEW YORK, ASSIGNOR TO GENEVA CUTLERY CORPORATION, OF GENEVA, NEW YORK, A CORPORATION OF NEW YORK.

SAFETY-RAZOR.

1,323,731.

Specification of Letters Patent.

Patented Dec. 2, 1919.

Application filed May 17, 1919. Serial No. 297,759.

To all whom it may concern:

Be it known that I, PHILIP H. UNSINGER, of Geneva, in the county of Ontario, in the State of New York, have invented new 5 and useful Improvements in Safety-Razors, of which the following, taken in connection with the accompanying drawings, is a full, clear, and exact description.

This invention relates to improvements in 10 mounts for razor blades and what are commonly called safety razors.

The object of this invention is to produce a mount which will hold, in operative position, the ordinary commercial blades 15 used in safety razors, cheap and durable in construction and of great utility.

The invention relates more particularly to the detailed construction and operation thereof, the advantages of which will more 20 fully appear from the following description taken in connection with the drawings in which—

Figure 1 is a perspective view of the safety 25 razor mount looking at it from the rear, in closed position holding the blade.

Fig. 2 is a section on line *a—a*, Fig. 1.

Fig. 3 is a section on line *b—b*, Fig. 1.

The razor mount comprises a base —1— 30 preferably formed of sheet metal, having its front portion bent downwardly as shown at —2—, from the body of the plate and preferably lying at an obtuse angle to the body of the plate to constitute when formed, as hereinafter described, a guard bar —3— 35 and a series of upwardly extending teeth —4—.

For this purpose the plate —1— has a portion cut away to form an elongated opening —5— bordered by relatively narrow 40 side walls —6— which together with the bar —3—, from which the teeth —4— extend, constitute the guard bar of the razor. The series of guard teeth —4— project into the opening —5— when the front portion 45 of the plate —1— is bent downwardly about an axis extending through the intermediate portion of the side walls —6—, these teeth extending preferably forwardly toward the blade —8— when properly seated within the 50 mount. The opening —5— extends some distance to the rear of the front edge of the blade —8— and as the teeth —4— terminate beneath the blade, there is left a free 55 passage between the blade for lather, etc., the front edge of the blade at the side por-

tions being supported by the side walls —6— which in turn are provided with stops —9— to properly limit and hold the blade —8— in position. These stops —9— may be formed in any suitable manner as by punching up parts of the plate —1— or in any other suitable manner. The blade —8— is held in place upon the base —1— by a holding and clamping member —10— connected to the rear of the base for pivotal or 60 rocking movement to permit the separation of the parts to an extent, thereby allowing removal of the blade and permit the easy cleaning of the structure. For this purpose the clamping member is formed with a 65 slightly curved body portion —11— and one edge thereof bent substantially U-shape, as shown in Fig. 2, and having its rear edge portions formed with any suitable number of eyes —12— adapted to engage and register laterally with eyes —13— upon the rear edge of the plate —1— so as to form a pivot 70 in connection with the rod —14—. While I have shown a number of these eyes, I 75 preferably use a lesser number for the reason that a lesser number will provide adequate strength for the purpose in hand, reduces the expense of manufacture and it is 80 much easier to keep the mount clean.

The plate —1— upon its rear face is provided with a boss or bushing —15— riveted or otherwise secured thereto and interiorly threaded, as shown, to receive the hardened steel plug —16—, the lower end of which is adapted to engage snugly with the handle —17—, as shown in Fig. 2. The upper end of the hardened steel plug, which extends through the plate —1—, terminates in a circumferential groove —18— adjacent to its upper end. —19— is a spring rod, 85 best shown in Fig. 3, mounted at each end in the flanges —20— of the clamping member —10— so that when the clamping member, holding the razor blade, is forced downwardly, this rod —19— will engage or snap 90 into the circumferential groove —18— and hold the clamping member which in turn carries the blade in a locked position.

To remove the blade it is only necessary 95 to exert pressure on the rear edge of the clamping member which will disengage with rod —19— from the recess —18— and allow it to rock sufficiently to remove the blade.

What I claim is:—

1. A mount for a razor blade, comprising 110

a base, one edge of which terminates in a guard, a clamping member hinged to said base and adapted to hold a blade therein, an interiorly threaded bushing secured to one side of said base and a plug engaging said bushing and having a circumferential groove on one end and its opposite end engaging the handle, a handle, a spring mounted in the clamping member and engaging said 10 groove to retain the clamping member in operable position.

2. A mount for a razor blade, comprising a base, one edge of which terminates in a guard, a clamping member hinged to said base and adapted to hold a blade therein, a 15

bushing secured in one side of said base, a plug engaging said bushing and having a groove in one end and its opposite end adapted to be pressed into a recess in the handle, a handle, a spring mounted in the clamping member and engaging said groove to retain the clamping member in operable position. 20

In witness whereof I have hereunto set my hand this 10th day of May, 1919.

PHILIP H. UNSINGER.

Witnesses:

RICHARD E. RITTER,
WILLIAM H. CHILSON.
